UNITED STATES PATENT OFFICE.

JOHN WILLIAM EMMERT, OF EATON RAPIDS, MICHIGAN.

ATTACHMENT FOR SHEARS.

SPECIFICATION forming part of Letters Patent No. 406,039, dated July 2, 1889.

Application filed July 15, 1887. Renewed March 1, 1889. Serial No. 301,814. (No model.)

To all whom it may concern:

Be it known that I, JOHN WILLIAM EMMERT, a citizen of the United States, residing at Eaton Rapids, in the county of Eaton and State of Michigan, have invented new and useful Improvements in Attachments to Shears, of which the following is a specification.

My invention relates to an attachment for shears or scissors; and it consists in the novel construction, arrangement, and adaptation of a metallic pressing-strip securely fastened thereto, which will be more fully hereinafter described, and pointed out in the claim.

The object of my invention is to provide an attachment to be used in connection with shears or scissors, whereby the names of subscribers to papers or periodicals, or the names of towns or cities, having previously been printed or written on strips of gummed or plain paper, can be cut off, and by a metallic strip be pressed on the paper, periodical, envelope, or wrapper. I attain this object by the device illustrated in the accompanying drawings, wherein like letters of reference indicate similar parts in the several views, and in which—

Figure 1 illustrates in perspective a pair of shears with my improved attachment applied in connection therewith. Fig. 2 is a detail perspective view of the said attachment. Fig. 3 is a perspective view showing a pair of shears having my attachment applied thereto and in position the slip of addresses.

A indicates the blade of a pair of shears or scissors, to the forward portion of which a metallic plate B is secured. This plate B is fastened to the blade A, and projects outwardly from the said blade of the shears at right angles from the cutting-edge. The under side of this strip is constructed thereby with a plain flat surface, which is adapted to come in contact with the top surface of the strip of paper containing the names being attached, the under side of which may have been previously covered with gum or mucilage.

The blade A, to which the attachment B is secured, is adapted to raise and lower from the strip of paper being cut; and to quicken the application of the cut strips my invention presses on the top surface of the said paper, cutting and at the same time pressing the end firmly against the main body of the paper,

periodical, envelope, or wrapper, and securing the same very rapidly.

It will be seen, upon reference to the drawings, that my device consists of a single strip of metal bent to form the flat presser-plate C, the brace D, and the securing-flange E. One edge of the presser-plate is secured to the outer side of the blade A of the scissors, so that the edge of said blade will be in the same plane with the under surface of the presser-plate. The securing-flange is secured to the upper edge of the blade, and the brace extends between the outer free edges of the securing-flange and the presser-plate, thereby preventing the bending of said plate and maintaining the flat surface thereof. The angle formed by the presser-plate and the brace is not a sharp angle, but is rounded, as clearly shown. This construction is advantageous, for the reason that should the strip pasted on the paper or other malleable matter form blisters, or not lie smoothly after being acted upon by the presser-plate, the device may be moved over the strip to remove the blisters and smooth out the strip. The round corner permits the device to move easily and readily over the strip, whereas a sharp corner would be apt to tear and destroy the pasted strip.

The device is very simple, and its construction is such that it may be made of very light material without destroying its efficiency or increasing the weight of the scissors to an appreciable degree.

Having thus described my invention, I claim—

A pair of scissors or shears provided with a device for attaching labels, the same consisting of a single strip bent to form the presser-plate C, secured to the blade of the scissors, the securing-flange E, secured to the upper edge of said blade, and the brace D, extending between the free edges of the plate and the flange, the corner formed by the brace and the plate being rounded, substantially as specified.

In testimony that I claim the foregoing as my own I have hereto affixed my signature in presence of two witnesses.

JOHN WILLIAM EMMERT.
